CLAIM

The ornamental design for a tower fan, as shown and described.

DESCRIPTION

The patent or application file contains at least one drawing executed in color. Copies of this patent or patent application publication with color drawing(s) will be provided by the Office upon request and payment of the necessary fee.

1. Tower fan

1.1. : Front

1.2. : Back

1.3. : Left

1.4. : Right

1.5. : Top

1.6. : Bottom

1.7. : Perspective

1.8. : Enlarged portion A encircled in reproduction 1.7

1.9. : Enlarged portion B encircled in reproduction 1.7

**1 Claim, 9 Drawing Sheets
(8 of 9 Drawing Sheet(s) Filed in Color)**
